UNITED STATES PATENT OFFICE

CHARLES MILLER, OF NEW YORK, N. Y.

DESIGN FOR A SHOE

Application filed June 7, 1933. Serial No. 48,319. Term of patent 3½ years.

To all whom it may concern:

Be it known that I, CHARLES MILLER, a citizen of the United States, residing in New York, in the county of New York and State of New York, have invented a new, original, and ornamental Design for a Shoe, of which the following is a specification, reference being had to the accompanying drawing, forming part thereof.

I claim:

The ornamental design for a shoe, as shown.

CHARLES MILLER.
